UNITED STATES PATENT OFFICE.

ERICK P. BERGMAN, OF CONCORDIA, KANSAS.

CAR-STEP.

No. 884,889.

Specification of Letters Patent.

Patented April 14, 1908.

Application filed September 14, 1907. Serial No. 392,926.

To all whom it may concern:

Be it known that I, ERICK P. BERGMAN, a citizen of the United States, residing at Concordia, in the county of Cloud and State 5 of Kansas, have invented new and useful Improvements in Car-Steps, of which the following is a specification.

This invention relates generally to car steps, and more particularly to that class in 10 which one of the steps may be automatically dropped to bring it close to the ground, thereby to obviate the necessity of employing boxes or the like, such as are commonly used on passenger and sleeping cars, and 15 which require the presence of an attendant, and further in which the said lowered step may automatically be returned to its normal position.

The object of the present invention is to 20 improve and simplify the construction of the step-lowering mechanism and step-raising mechanism, and to render it possible for a person to use the step in the ordinary manner without projecting the lower step. Further- 25 more, to provide a novel form of platform which will normally close access to the steps, and may be utilized for purposes of observa- 30 tion, and which will, when a step has been projected operate automatically to return such step to its normal position.

With the above and other objects in view, as will appear as the nature of the invention is better understood, the same consists in the 35 novel construction and combination of parts 35 of a car step, as will be hereinafter fully described and claimed.

In the accompanying drawings, forming a 40 part of this specification, and in which like characters of reference indicate correspond- 45 ing parts throughout: Figure 1 is a view in side elevation of a car step constructed in accordance with the present invention. Fig. 2 is a view in rear elevation.

The step frame 1 is secured to a car plat- 45 form in the usual or any preferred manner, and as its particular construction forms no part of the present invention, detailed de- 50 scription thereof is omitted.

The present novelty resides in the mech- 50 anism for projecting or lowering the lower- 55 most step 2 of the car steps. This step, as shown in Fig. 1, is provided with an angular extension 3 that is adapted, when the step is raised, to bear against the rear side of the step frame, and when lowered, to consti-

tute a guard that will prevent a person's feet from slipping in between the projected or lowered step and the next adjacent one.

Secured to the step 2 are two bars or rods 4 that work in guides or keepers 5 secured to the rear sides of the step frame and preferably to the riser of one and platform of the other as shown in Fig. 2. Of these guides four are employed in this instance; but it is to be understood that a greater number may be utilized if desired. The bars 4 are preferably, though not of necessity, rectangular in cross section, and the openings in the guides for their reception are of the same contour.

Pivotedly connected to each of the bars 70 intermediate of its ends is the lower end of a link 6, the upper ends of the two links being connected with cranks 7 carried by a crank-shaft 8 supported in hangers 9 on the two sides of the step-frame.

One end of the shaft 8 is provided with a crank 10 that projects through a slot 11 in the lower end of a push-rod 12, the upper end of which is provided with an inturned flange 13 that constitutes an abutment. The 80 push-rod 12 works in a guide 14 secured to one side of the step-frame and to this guide is pivotally connected the lower end of a spring-pressed dog 15, the upper end of which is provided with a hook 16 that is adapted to inter- 85 lock with the abutment 13 and hold the same normally depressed. The hook extends a sufficient distance above the side rails of the step-frame to permit of its being engaged by the toe of an attendant when it is desired to 90 release the push-rod 12 to permit the step 2 to drop.

Hinged to one side of the step frame is a platform 17 which is of a width to span the space between the two sides of the step-frame 95 and to rest upon the abutment, whereby accidental release of the step 2 will be prevented, it being seen that before the dog 15 can be released, or the push-rod 12 can lift, the platform must be raised to the position 100 shown in full lines in Fig. 2.

In the use of the apparatus, the conductor or other attendant, lifts the platform 17 and trips the dog, whereupon the push-rod 12 is released, and the step 2 by gravity will drop to 105 the position shown. When the step 2 is to be raised, the attendant either presses upon the abutment 13 with his foot or will drop the platform and step upon the same, whereupon the crank-shaft 8 will be rocked and 110

cause the step 2 to be raised and be locked against accidental falling.

What I claim is:

1. In a railway car-step, the combination with the usual steps of a drop-step, a pair of bars connected therewith, a crank-shaft, a pair of links connecting the bars and the crank-shaft, the outer extremity of the shaft being provided with a crank, a push-rod provided with a slot through which the crank extends, and a dog having a hook to engage with the push-rod to hold the same normally depressed.
2. In a railway car-step, the combination

with the usual steps, of a drop-step, a vertically disposed push-rod provided with an abutment, a crank-shaft with which the push-rod coacts, a connection between the drop-step and the crank-shaft, a spring-pressed dog arranged in the path of movement of the abutment, and a platform adapted to contact with the abutment to maintain the push-rod normally in depressed position.

ERICK P. BERGMAN.
